(57) **CLAIM**

The ornamental design for an electric range, as shown and described.

DESCRIPTION

FIG. 1 is a front perspective view of a control panel for electric range showing our new ornamental design;

FIG. 2 a front view thereof;

FIG. 3 is a top view thereof; and,

FIG. 4 is a right side view thereof, with the left side view thereof being a mirror image thereof.

The broken lines represent environment and form no part of the claimed design.
